Fig. 1

Fig. 2

Fig. 3

FIGURE 1 is a front perspective view of a space condition responsive instrument embodying my new design. The perforations are repeated throughout the front area;

FIGURE 2 is a side view of the instrument shown in FIGURE 1 looking toward the right side of FIGURE 1; and

FIGURE 3 is a bottom view of the instrument shown in FIGURE 1.

The essential features of the design reside in the portions shown in full lines.

I claim:

The ornamental design for a space condition responsive instrument, substantially as shown and described.
